UNITED STATES PATENT OFFICE

2,324,939

RAILWAY TRAFFIC CONTROLLING
APPARATUS

Ronald A. McCann, Swissvale, Pa., assignor to
The Union Switch & Signal Company, Swiss-
vale, Pa., a corporation of Pennsylvania

Application September 3, 1942, Serial No. 457,133

4 Claims. (Cl. 246—3)

My invention relates to railway traffic controlling apparatus, and more particularly to train indication means for use in connection with centralized traffic controlling systems for single track railroads.

In systems of this character, it is customary to divide the track into blocks each extending from one passing siding to the next, and to govern train movements through the blocks by means of an absolute permissive block system in which the signals are generally controlled over line circuits, the energization of which is dependent upon the positions of trains and their direction of movement, as reflected by track circuits, the head block signals which govern traffic movements into the single track blocks being also subject to manual control by means of a communication system of a suitable type. It is also the practice to provide an illuminated track diagram at the office for the guidance of the operator, comprising a miniature representation of the controlled stretch of track having indication lamps mounted thereon at spaced points, the lamps being governed by means of the communication system to indicate when trains are passing the corresponding trackway stations. Since these stations correspond generally to the locations from which "OS" reports of the passage of trains are transmitted by wire by local operators in manual train dispatching systems, the lamps are commonly designated as "OS" lamps, and each is controlled in accordance with the condition of a short "OS" section including the track switch at the entrance or exit end of the block.

In systems of this character it has been found desirable to indicate the presence of a train, whenever it may be in the controlled territory, by the provision of one or more additional lamps on the track diagram. These additional lamps provide a "block indication," indicating the presence of a train in the controlled territory at such times as the "OS" indication lamps are not lighted, even though the territory is occupied, as, for example, when a train has passed out of the "OS" section at the entrance end of the block but has not yet reached the corresponding "OS" section at its exit end. One manner in which this has been accomplished has been by the provision of "approach" indications, to indicate when a train occupies one or the other of two approach zones, located within but adjacent to the ends of the block, the transmission of these indications by the communication system being effected by approach relays controlled over additional line wires, as shown, for example, in

Letters Patent of the United States No. 2,192,988 granted December 21, 1937, to E. M. Allen, for Railway traffic controlling apparatus.

Such approach relays are provided primarily to control the switch locking when a train is approaching the exit end of a block, and the more recent practice is to omit the approach control of the switch locking to reduce the cost of the system, particularly as installed on roads having relatively light traffic. In such systems approach relays are not available, and in any case the use of approach relays to provide a block indication requires the approach zones to be extended so that they overlap, as explained in the Allen patent, this generally requiring the installation of additional line wires.

The object of my invention is to provide a block indication which correctly indicates the condition of a single track block at all times through the medium of the existing communication system and which does not require the installation of any special apparatus whatever in the field.

One form of apparatus embodying my invention will now be described and the novel features thereof will then be pointed out in claims.

Referring to the accompanying drawing, the track diagram at the top illustrates, in condensed form, the track rails of a typical single track block equipped with continuous track circuits, each provided with a track relay TR, the block extending between the ends of two passing sidings identified by the track switches 1 and 7. Train movements through the block are governed by a centralized traffic control system, including an automatic block signaling system of the absolute permissive type controlled by the track relays TR, together with central office control of the opposing head block signals, such as the signals RA2 and LA2, by means of the signal control relays R2HS and L2HS, the latter being governed by means of a suitable communication system from a central office shown diagrammatically in the lower portion of the view. The block signaling system as shown corresponds generally to that disclosed in Letters Patent of the United States No. 2,077,817, granted April 20, 1937 to H. S. Young and R. A. McCann, for Railway traffic controlling apparatus.

As shown, the block is provided with only one pair of intermediate signals 4 and 5, but in practice the block may include several intermediate sections and additional signals having circuits similar to those shown for signals 4 and 5. Each signal is controlled automatically by the

track relays TR of the track sections in advance thereof, through the medium of a line relay HR and a repeating relay HP, each such relay being identified by a prefix corresponding to the signal it controls. Each intermediate signal has the usual directional stick relay S to provide for permissive following train movements. At each end of the block a time locking relay AS is provided, controlled by the associated head block signals and signal control relay. Each relay AS is released when one of the associated signals is cleared, to open the circuits for the opposing head block signals, and to maintain them open in case the associated signal is manually put to stop, for a predetermined time interval measured by a time element relay TER.

The communication system connecting the central office with the various stations comprising the head block signal locations may be of any suitable type, but preferably is of the selective or code type, in which communication is established intermittently between the control office and various stations over a single pair of line wires, a suitable system being shown, for example, in the Letters Patent of the United States No. 2,229,249, granted January 21, 1941, to L. V. Lewis, for Remote control systems. Direct wire control may also be used, and as illustrative of either form, direct wire connections are shown herein extending from one terminal B of a suitable source of current over contacts of signal levers 2SG and 8SG at the office through the signal control relays R2HS and L8HS in the field, to the other terminal C of the same source, and likewise over back contacts of the line relays R2HR and L8HR associated with the head block signals, through the windings of corresponding indication relays R2HK and L8HK at the office, the latter relays controlling a block indication relay 2-8BK in accordance with my invention. Similarly, back contacts of the track relays 1TR and 7TR for the "OS" or detector track sections including the track switches 1 and 7 control the indication relays 1TK and 7TK, and front contacts of the indication relays 1TK, 7TK and 2-8BK control corresponding lamps E mounted in the operator's track diagram as shown.

The block signaling system operates in the manner described in the Young and McCann patent hereinbefore referred to, the line relays HR for both directions being normally energized in tandem as shown, and the track diagram being normally dark.

It is believed that the apparatus of my invention may be readily understood from a description of its operation, and accordingly it will be assumed that with the apparatus in the condition shown in the drawings, the operator at the office moves lever 2SG to the right, thereby energizing the signal control relay R2HS with the object of clearing signal RA2 for a train movement through the block from left to right. A circuit is thereby completed from one terminal B of a suitable local source of current over front contact 10 of relay R2HR, normal contact 11 controlled by switch 1, front contact 12 of relay R2HS through relay RA2HP to the other terminal C of the same source. Relay RA2HP therefore becomes energized to cause signal RA2 to indicate clear, and by opening its back contact 13 opens the circuit for relay R2AS, which releases, and in turn opens contact 14 in the circuit for relay 4HR. Relay 4HR therefore releases, causing the indication of the opposing

intermediate signal 4 to change from caution to stop, and relay 4HR opens contact 15 in the circuit for the line relay for the next signal in the rear, in this case relay L8HR. Relay L8HR releases, closing its back contact 16, thereby energizing the office indication relay L8HK, and relay L8HK then closes contact 22 in the circuit for relay 2-8BK; the latter relay, however, does not pick up at this time.

- 10 When the approaching train passes signal RA2 at clear to enter the switch section at the entrance end of the block, the track relay 1TR is released and by opening its contact 18 releases relay R2HR, the latter relay in turn, by opening contact 19, releasing relay RA2HP to restore signal RA2 to stop. The closing of back contacts 19 and 10, respectively, of relays 1TR and R2HR causes the energization of the indication relays 1TK and R2HK, relay 1TK closing its contacts 20 to effect the lighting of the "OS" lamp 1E, and relay R2HK closing contact 21 to complete the circuit for relay 2-8BK, which picks up, closing contact 25 to light the block indication lamp 2-8E.
- 25 The operator may now restore lever 2SG to normal to release relay R2HS and thereby effect the reenergization of relay R2AS over its pick-up circuit including back contacts 23 and 24 of relays R2HS and 1TR as in the system of the Young and McCann patent, thereby closing contact 14 in the circuit for relay 4HR, but relay 4HR will remain deenergized by the release of one or more of the track relays 1TR, 3TR and 4TR as long as the train occupies any one of these sections. Also relay L8HR will be held deenergized by the release of one or more of the track relays 3TR, 4TR, 5TR, 6TR and 7TR as long as the train occupies any portion of the block. Lamp 1E will be extinguished by the release of relay 1TK when relay 1TR is reenergized as the train vacates the "OS" section at the entrance end of the block, but lamp 2-8E will remain lighted until the train vacates the entire block, relay L8HK being held energized by relay L8HR, and holding relay 2-8BK energized over a stick circuit including front contacts 26 and 17 until after the last track relay 7TR is reenergized.

- 50 It will be understood that as the train passes through the block, the directional stick relay 5S will become energized upon passing signal 5, and that relay R2HR will be reenergized when the track relay 4TR picks up, by current of reverse polarity supplied from the negative terminal N of a suitable source connected to the lower back contact of relay 5HF. Relay R2HK will therefore release, but without affecting relay 2-8BK, which is now held energized over a stick circuit which is independent of relay R2HK.
- 60 It will be readily apparent from the symmetry of the circuits that with the apparatus in the normal condition, as shown, the movement of lever 8SG to the left will clear signal LA2, to allow a train moving from right to left to enter the block, and that the apparatus will then function in a manner similar to that described. The block indication lamp 2-8E will be lighted by such train, the principal difference being that in this case relay 2-8BK will be held energized over a stick circuit including contact 27 of relay R2HK in place of contact 26. Relay L8HK will release when the rear of the train passes signal 4 and relay L8HR will become energized over a front contact of the directional stick relay 4S.
- 70 The indication relays R2HK and L8HK replace

the approach indication relays as used heretofore as, for example, in the above-mentioned Allen patent, and it will be clear therefore that the object of my invention is attained by the provision of but one additional relay, namely relay 2-8BK, at the office, and without any additional apparatus in the field.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination with a stretch of railway track comprising a single track block divided into track sections, a track relay for each track section, a line relay for each direction of traffic through said block, means for energizing each line relay when all said track relays are picked up and also when one or more of said track relays are released by a train moving in the corresponding direction at an intermediate point in said block, a two position indication relay at a central office, means for operating said indication relay to one position upon the release of both said line relays and to its other position upon the energization of both said line relays, and a block indicator controlled by said indication relay to indicate when it occupies said one position.

2. In combination with a stretch of railway track comprising a single track block divided into track sections each having a track relay, a head block signal for each direction of traffic through said block, a line relay for each signal, line circuits controlled by the track relays for energizing each line relay when the entire block is unoccupied and also when a train moving in a corresponding direction passes an intermediate point in said stretch, means for manually clearing either signal effective only when its line relay is energized, to establish the direction for traffic movements through the block, means responsive to the clearing of either signal to re-

lease the line relay for the other signal, a two position indication relay, means for operating said indication relay to one position in response to the release of both said line relays and to its other position in response to the energization of both said line relays, and a block indicator controlled by said indication relay to indicate when it occupies said one position.

3. In combination with a stretch of railway track comprising a single track block divided into track sections each having a track relay, a line relay for each direction of traffic through said block, line circuits controlled by the track relays for energizing each line relay when the entire block is unoccupied and also when a train moving in a corresponding direction passes an intermediate point in said stretch, a stick relay, a pick-up circuit for said stick relay including two contacts in series, said contacts being both closed to complete the circuit only when both line relays are released, a stick circuit for said stick relay including its own front contact and two contacts in multiple, said last named contacts being both open only when both line relays are picked up, and a block indication lamp controlled by a contact of said stick relay.

4. In combination with a stretch of railway track comprising a single track block divided into track sections each having a track relay, a line relay for each direction of traffic through said block, line circuits controlled by the track relays for energizing each line relay when the entire block is unoccupied and also when a train moving in a corresponding direction passes an intermediate point in said stretch, an indication relay at a central office for each line relay, means for energizing each indication relay when the associated line relay is released, a stick relay, a pick-up circuit for the stick relay including front contacts of both indication relays in series, a stick circuit for the stick relay including front contacts of both indication relays in multiple, and a block indication lamp controlled by a contact of said stick relay.

RONALD A. McCANN.
